AUTOMATIC SAFETY SASH LATCH
Zan Ruchin, 5 E. 41st St., Bayonne, N.J. 07002
Filed Mar. 9, 1965, Ser. No. 438,188
4 Claims. (Cl. 292—228)

This invention relates to sash locks for attachment to double hung windows. The distinctive feature of this invention is the automatic lock unit which makes unnecessary an additional operation to lock the sash, once it has been closed. Also, the sash lock may be adjusted to permit the bottom sash to be opened slightly for ventilation, or the bottom sash may be closed and the upper sash opened slightly for ventilation, or by additional adjustment of the sash lock, both sashes may be slightly opened, top and bottom, for improved ventilation, by permitting air to circulate within the room.

With the sash locks in lock position, two sash locks are recommended for balanced operation and added safety, it is impossible to move the sashes. With the sash locks adjusted for ventilation, it is impossible to move the sashes beyond the position for which the sash locks have been set, except to close and lock them. The sash locks are tamper-proof, due to their unexposed positions at the extreme sides of the sash, and particularly because of a flat spring attached to the bottom of the upper sash bar, which discourages any attempt to release the locking bracket firmly wedged under a stop block, to be explained in detail in the following paragraphs.

FIGURE 1 is a perspective front view of the invention in place on a window sash. Two Automatic Safety Sash Locks, thereafter to be designated as sash locks, are shown mounted on both ends of the sash. FIGURE 2 is a cross section through 2—2 of FIGURE 1, shown per se. FIGURE 3 is a cross section through 3—3 of FIGURE 2. FIGURE 4 is an exploded view of four elements of the locking unit. FIGURE 5 is a bottom perspective view of the locking bracket, the fifth element of the locking unit. FIGURE 6 is a perspective view of the bottom section of the upper sash bar.

Referring to the drawings in greater detail, W—W represents a double hung window at the right and left extremities of which have been attached sash locks. Reference will be made to the left sash lock which is in full view, FIGURE 1. The upper sash bar 1 is attached to the bottom of the upper sash by screws Sc, through holes 1s and 1bs, more clearly indicated in FIGURES 2 and 6. The upper sash bar is attached with sufficient clearance to the left of the sash to permit the locking unit, FIGURES 1 and 2, to ride freely when the lower sash is raised. With the upper sash bar in place, the locking unit is next attached to the top of the lower sash by means of screws through four holes, 4s, in the base plate shown in FIGURES 3 and 4.

The constructional details and operation are as follows: The upper sash bar 1, attached to the upper sash, is a narrow steel plate bent outwards along its longitudinal edges at about 45 degrees. Three stop blocks of steel 1a, FIGURES 1, 2, 3 and 6, are welded at regular intervals along the inner surface of the upper sash bar 1, so that the top stop block is set between the upper edge and the top screw hole 1s, and the bottom stop block slightly above the bottom screw hole 1bs, FIGURES 2 and 6.

A Phosphor bronze flat spring 1b, FIGURE 6, is welded at its upper portion to the bottom of the upper sash bar 1, just below the bottom stop block 1a. The

2

bottom screw hole 1bs passes through the upper portion of the flat spring whose bottom portion is free and is bent outwards slightly beyond the angled edges of the upper sash bar. The purpose of the flat spring is to prevent a thin piece of metal, such as a knife blade, from being inserted between the sashes, in closed position, and between the locking unit and upper sash bar, for the purpose of disengaging the tongue 2a of locking bracket 2, FIGURE 2, for forced entry.

10 The locking unit which is attached to the top of the lower sash is comprised of the following elements: A base plate 4, FIGURE 4, is perforated by four screw holes 4s, along two opposite edges, and is bent at two corners along edge 4e to form two small brackets 15 4a, perforated 4c, to receive a pin 4b. Welded to the base plate 4 is the base bracket 3, in the manner shown in FIGURES 1, 2 and 3. The base bracket is perforated by a rectangular hole 3s to receive the Phosphor bronze spring 2b, attached to the bottom of the locking bracket 2, FIGURES 5 and 2, which rests on the base bracket. Locking bracket 2 rotates about the pin 4b, FIGURES 1, 2 and 3. Locking tongue 2a, FIGURES 2 and 5, on the upper edge of locking bracket 2, snaps under the stop blocks 1a on the upper sash bar 1, and serves to lock 25 the sash at any one of three positions, FIGURES 1 and 2. Sliding element 5, FIGURES 3 and 4, is welded to the vertical section of base bracket 3. It is a short section of steel, bent inwards about 45 degrees at its two vertical edges and serves to guide the locking unit up and down 30 the length of the upper sash bar 1.

The rectangular hole 3s in base bracket 3, FIGURE 4, in receiving the Phosphor bronze spring 2b, FIGURE 2, makes it possible to disengage locking bracket 2 from the stop blocks 1a, so that the locking bracket rests flat upon base bracket 3. Phosphor bronze spring 2b may be attached at its forward to the under side of locking bracket 2, as shown in FIGURE 5, leaving the other end free to move within rectangular hole 3s in base bracket 3, FIGURE 2, or it may be attached at its far end to the upper face of base plate 4 near edge 4e, and its free forward end projecting through rectangular hole 3s, free to move under locking bracket 2.

The above description is presented as an embodiment of the invention. Component elements, therein, may be substituted by other elements which may perform substantially similar functions. These elements may now be in use or previously invented, but may be considered as being within the scope of the appended claims.

50 I claim:

1. A window sash latching device comprising: a vertically extending keeper plate adapted to be secured adjacent a movable sash and having latch abutment plates secured flatly thereon and spaced along its length, the opposite vertical edges of said keeper plate extending angularly outwardly; a spring-projected pivotally-mounted latch element having means adapting said latch element for securement to the sash, and having a portion for engagement with an edge of a selected one of said abutment plates; and a guide plate, secured to said means between said latch element and said keeper plate and having opposite vertical edges thereof angularly inwardly extending for guiding engagement behind the edges of said keeper plate.

65 2. A latching device as defined in claim 1, wherein said abutment plates are welded to said keeper plate.

3. A latching device as defined in claim 1, wherein a spring strip is secured to said means and arranged to

form a bolt guard to prevent release of said latch element by extraneous means.

4. A latching device as defined in claim 1 in combination with a window sash and a second latching device operatively associated therewith.
